CLAIM

The ornamental design for a combined door opener and escutcheon unit, as shown and described.

DESCRIPTION

FIG. 1 is a reduced front perspective view of the outer elements of the combined door opener and escutcheon unit showing my new design, shown separately for clarity of illustration and the broken line showing of a portion of a door being for illustrative purposes only; FIG. 2 is a front elevational view thereof; FIG. 3 is a top plan view thereof; FIG. 4 is a bottom plan view thereof; FIG. 5 is a right side elevational view thereof; FIG. 6 is a left side elevational view thereof; and FIG. 7 is a front elevational view of the inner elements, again shown separately for clarity of illustration. The rear surfaces of the individual elements are unornamented.
